FUEL INJECTING DEVICE FOR INTERNAL-COMBUSTION ENGINES

Theodore N. Saaty, Providence, R. I.

Application February 23, 1949, Serial No. 77,857

14 Claims. (Cl. 261—37)

1

This invention relates to a fuel atomizing device for use on internal combustion engines.

The usual carburetor on an internal combustion engine is characterized by the fact that all air entering the carburetor passes through a venturi into which a suction fuel nozzle extends. The mixing of the air passing through the venturi and the fuel leaving the nozzle occurs at the tip of the nozzle. At the lower speed range of the engine the slow rate at which the air flows through the venturi produces a very low suction on the fuel nozzle therein, insufficient to lift fuel from it. To overcome this difficulty, a separate idle fuel nozzle is positioned on the intake manifold side of the throttle where there is a high suction. These two fuel systems are interconnected by passages and air vents of minute size which often times become clogged with a foreign residue in the fuel or air. When a change from closed to open position of the throttle is made there is great imperfection in fuel supply as the demand for fuel changes from the idle system to the main system of fuel supply. This difficulty causes rough running of the engine. Also, this causes slow response to a demand for an increase of engine speed, so that an acceleration system is required to temporarily supply wet fuel to supplement the fuel delivery from the main system. Over a low range of speed with the engine under load there is insufficient fuel drawn from the fuel nozzle to supply the demand of the engine, and in an automobile a shifting of the transmission connected to the engine is required so as to provide a sufficient speed in the engine to create the necessary suction to furnish the required fuel so as to obtain added engine torque.

The principal object of the invention is to improve generally on the usual carburetor construction in present use on an internal combustion engine to the end that a more simplified construction may be had.

Another object of the invention is to avoid passages and air vents of minute sizes which may become clogged, and provide for a more accurate metering of fuel at all throttle positions to provide a more efficient and economical consumption of fuel.

A more specific object of the invention is the provision of a fuel atomizing device of this character wherein raw fuel is atomized and ejected into the air flow independently of engine suction.

Another object of the invention is the provision of fuel atomizer of this character wherein fuel will be fed to the fuel nozzle and atomized under positive pressure.

2

Another object of the invention is the provision of a fuel atomizing device having self-contained means to supply fuel to the fuel nozzle when external means are inadequate to furnish sufficient fuel.

Another object of the invention is the provision of a fuel atomizing device having a single nozzle for supplying fuel at all throttle positions.

Another object of the invention is the provision of a fuel atomizing device which will be automatically operable to supply a richer fuel mixture on demand of engine performance without change in throttle position.

Another object of the invention is the provision of a fuel atomizing device which will be automatically operable by engine suction to supply a richer fuel mixture on drop of engine suction due to increased load thereon.

Another object of the invention is the provision of a fuel atomizing device which is so constructed that its operation will be unaffected as to position, attitude or the jostling thereof.

Another object of the invention is the provision of a fuel atomizing device having manually operable means to maintain or alter the ratio of fuel mixture.

Another object of the invention is the provision of a fuel atomizing device which will be cam controlled to maintain or alter the ratio of fuel mixture.

Another object of the invention is the provision of a fuel atomizing device of this character wherein the fuel will be ejected in the air flow under positive pressure.

Another object of the invention is the provision of a fuel atomizing device of this character which is so constructed as to deliver fuel into the air stream in a more finely atomized state.

Another object of the invention is the provision of a fuel atomizing device of this character which is so constructed as to be readily adjustable for each engine to which the device may be attached.

With these and other objects in view, the invention consists of certain novel features of construction, as will be more fully described and particularly pointed out in the appended claims.

In the accompanying drawings:

Figure 1 is a side elevational view of a fuel atomizing device for an internal combustion engine, embodying my invention;

Figure 2 is a similar view looking at the opposite side of the device shown in Figure 1;

Figure 3 is a plan view of the device looking down thereon;

Figure 4 is a fragmental portion of the device shown in Figure 1 with certain parts omitted and showing control elements thereof in a position different than that shown in Figure 1;

Figure 5 is a fragmental portion of the device shown in Figure 1 with certain parts omitted;

Figure 6 is a side elevational view looking in the direction of the arrows on line 6—6 of Figure 1;

Figure 7 is an elevational view looking in the 10 direction of the arrows on line 7—7 of Figure 3;

Figure 8 is a sectional view taken substantially along line 8—8 of Figure 3;

Figure 9 is a sectional view taken substantially along line 9—9 of Figure 8;

Figure 10 is a central elevational sectional view taken substantially along line 10—10 of Figure 1;

Figure 11 is an elevational view of a needle valve employed in the device;

Figure 12 is a plan view of a detail; and

Figure 13 is a diagrammatic view of my device attached to an internal combustion engine.

In carrying out my invention, I provide a single nozzle to inject fuel into the air flowing to the intake manifold of an internal combustion engine at all positions of the throttle independent of the engine suction. This is accomplished by providing for the ejecting of fuel from the nozzle in the form of a fine mist under pressure above atmospheric. This pressure may be supplied by the usual fuel pump mechanism of the engine. The nozzle is constructed so as to be valve controlled whereby the quantity of fuel ejected therefrom may be metered in proper amounts to provide for engine requirements at all speeds and loads thereon. The valve is preferably of the needle type which is mounted for movement so as to vary the fuel passage in the nozzle and is actuated through a series of linkages which is operated both manually and mechanically. The manual control is by means of a cam mounted for rotational movement and may be connected to be operated by the usual accelerator pedal of the automobile.

The cam which is differently cut for different engine characteristics operates to provide through the linkages movement of the valve in amounts whereby fuel will be metered at a constant mixture ratio in accordance to engine demand and load thereon.

Preferably I relate the mechanically controlled valve operating mechanism to the engine suction which varies with the position of the throttle and the speed of the engine. A means to this end which has been found satisfactory is in the form of a piston which is moved in one direction by engine suction and in the other direction by spring pressure. The motion of the piston which is produced when the suction of the engine drops such as occurs when the engine speed is reduced under load is employed as a means for controlling the fuel valve. Thus, there is provided a valve mechanism directly responsive to the engine demand under load.

Referring to the drawings for a more detailed description of the invention, 15 designates generally a fuel atomizer and metering device for use on an internal combustion engine. The device comprises essentially an air conduit 16 through which a flow of air may be had, a fuel nozzle 17 positioned within the conduit 16 for discharging fuel into the air flow to mix therewith, a reservoir 18 (see Fig. 10) for supplying fuel to the nozzle under a predetermined positive pressure, and a mechanism 19 for controlling

the discharge of fuel from the nozzle 17. The term positive pressure is herein employed to designate a pressure above atmospheric.

The air conduit 16 may be made in any appropriate manner and comprises a body 20, the lower end of which has a mounting flange 21 extending at substantially right angles to the body 20 and is provided with openings 22 for receiving bolts 23 to attach the device 15 to the intake manifold 24 of an internal combustion engine so as to provide an air flow through the conduit 16 by means of engine suction as is usual in devices of this character. The air flow through the conduit 16 is controlled by means of a throttle valve 25 (see Fig. 1) mounted on a suitable shaft 26 which is journaled in the walls of the body 20 at the upper end portion thereof. One end of the shaft 26 extends beyond the walls of the body 20 and carries a crank arm 27 to turn the shaft 26 so as to move the valve 25 to open or closed position, as conditions may require.

In order to manually operate the valve 25 from a remote location, as is usual in devices of this character, a shaft 28 (see Fig. 2) is journaled in the lower portion of the wall of the body 20 in the plane with the shaft 26 passing through the axis of the body 20 and with the end portions 29 and 30 thereof (see Fig. 10) extending beyond the body 20. A crank arm 31 is adjustably secured to the portion 29 and extends in the same general direction as the crank arm 27. A rod 32 has its end portions pivotally attached to the arms 27 and 31 such as by means of similar connections 33 whereby motion of the shaft 28 will be transmitted to the shaft 26. The end portion 30 is also provided with a crank arm 34 which is adjustably secured thereto such as by means of a screw 35 (see Fig. 10) and has a usual spherical projection 36 thereon to which there may be attached a usual operating wire or rod (not shown) extending to the accelerator pedal (not shown) of the vehicle to which the engine is related. At closed throttle the peripheral edge of the valve 25 will be set as to be spaced from the walls of the body 20 as at 37, a distance sufficient to permit a predetermined restricted air flow thereby.

The fuel nozzle 17 is mounted to be within the body 20 inwardly of the valve 25 with the discharge end thereof at a position to eject the fuel in the general direction of the air flow through the body 20. This nozzle 17 may be of any suitable manufacture operable to discharge fuel in a fine mist into the air flow so as to more readily mix therewith in proportion to meet engine requirements. In the present instance, the nozzle 17 (see Fig. 10) is formed of a cylindrical body 38 with the upper and lower portions thereof externally threaded as at 40 and 41. The body 38 has a bore 42 extending therethrough with an intermediate portion 43 thereof reduced in diameter providing shoulders 44 and 45. The body 38 is also provided with oppositely disposed hollow stem portions 46 and 47 opening into the bore 42. The stem portion 46 is internally threaded as at 48 and the outer end of stem 47 is externally threaded as at 49.

The upper end of the bore 42 is capped by a closure 50 which has threading engagement with the threaded portion 40 and the lower end of the bore is closed by means of a wall 51 having a central tapered opening 52 which forms a knife-edge valve seat 53. A wall 54 having a plurality of fuel passages 55 and a central flanged opening

56 is positioned to rest upon the shoulder 44 and may be secured in position thereon in any appropriate manner such as by a friction fit. A similar wall 51 having fuel passages 58 therein and a central flanged opening 59 in an axial line with the opening 56 is positioned to engage the shoulder 45 and is maintained in spaced relation with the wall 51 by means of a collar 60. A nut 61 having engagement with the threaded portion 39 has a central opening which provides an annular flange 62 to engage the marginal edges of the wall 51 whereby to secure the walls 51 and 57 to the body 38.

The fuel in passing through the nozzle will impinge upon the knife edge 53 and will break up into a fine mist. In order to enhance the breaking up of the fuel into a finer mist, the fuel passages 58 in the wall 57 are provided with an inclined flanged wall portion 63 (see Figure 10). These flanges may be raised from the stock of the wall 57 in a manner similar to that providing a louvre opening. The fuel passing through the passages 58 will be guided to move circularly in the space between the walls 51 and 57 so as to add impetus to the movement of the fuel and increase the impact thereof against the knife edge 53. The flow of air past the nozzle tip will create a small vacuum area about the valve seat 53 to further enhance the breaking up of the fuel into a fine mist.

The opening 52 is controlled by means of a needle valve 64 which is supported and guided through the openings 56 and 59 in the walls 54 and 57. Valve 64 is biased into engagement with the valve seat 53 by means of a compression spring 65, one end of which engages with the wall 54 and the other end engages an abutment 66 on the stem of the valve 64. In order to lift the valve 64 from the seat 53 against the pressure of the spring 65, the upper end portion of this valve stem is provided with a flanged portion 67 (see Figure 11) which is engaged by a cam 68 which, in the present instance, is of a circular shape and may be made integral with a shaft 69 journaled in the stem 41. The cam 68 has a sector cut out thereof providing a radial surface 70 positioned to engage beneath the flange 67. Turning the shaft 69 in the proper direction will lift the valve 64 from the valve seat 53. The position of the surface 70 may be adjusted in relation to the flange 67 by means of turning the shaft 69, a slot 71 on the end extremity of the shaft being provided for receiving a tool or the like for turning the shaft.

The reservoir 18 (see Figs. 2, 3, 7 and 8) is made a separate unit and of cylindrical formation providing a circular side wall 72 having an inlet opening 73 (see Fig. 8) to which may be secured a usual extension 74 (see Fig. 2) carrying a coupling 75 for attaching a tube thereto leading to a fuel pump P of the engine (see Fig. 13). The wall 72 is provided at one end with an annular flange 76 (see Fig. 10) which extends inwardly thereof and at the other end with an end wall 77 in which an outlet opening 78 is provided. The reservoir 18 is attached to body 20 such as by means of brackets 79 and 80 (see Fig. 3) welded in position to the wall 77 and extending into engagement with the body 20 and detachably fastened thereto such as by means of cap screws 31.

In the present instance the nozzle 17 is secured to the reservoir 18 which is fixed to the body 20; accordingly, the body 20 is provided with an opening 82 (see Fig. 10) in the side thereof and is of a dimension to pass the nozzle 17 therethrough.

A closure 83 is of a size to be tightly received in the opening 82 and is provided with a hollow projection 84, the end portion of which is threaded as at 85. The closure 83 is fastened to the outer side of the wall 77 such as by welding thereto and is positioned thereon at a location to align the bore of the stem 84 with the opening 78. The nozzle 17 is secured and supported by the projection 84 engaging the stem 46. Thus, a support is provided for the nozzle 17 with a conduit 86 extending from the reservoir to the bore 42 for the passage of fuel therethrough. The opposite side of the body 20 is provided with an opening 87 through which is passed the stem 47.

The fuel is supplied to the reservoir 18 by means of the pump P (see Fig. 13) forming part of the equipment of the usual internal combustion engine and is maintained at a uniform pressure above atmospheric and regulated by means of a pulsating diaphragm 88. The outer marginal edge of the diaphragm engages the flange 76 and is secured in such position by means of a ring 89 which lies over the marginal edge of the diaphragm and is secured to the flange 76 by means of cap screws 90. In order to equalize the pulsation of the fluid in the reservoir 18, a disc 91 is positioned to engage the diaphragm centrally thereof, and this disc in turn is engaged by flat spring 92 which extends diametrically from side to side of the reservoir and is held in position by means of a strap 93, the end portions of which are secured to the flange 76 such as by means of cap screws 94 (see Fig. 2). The end portions of the springs are provided with tabs 95 which are turned at right angles so as to engage the edges of the strap 93. The pressure of the spring 92 is chosen so as to be slightly less than the pressure of the pump through which fuel is supplied to the reservoir 18; thus, fuel under pressure above atmospheric will flow through the conduit 86 into the nozzle 17 to be discharged therefrom in amounts according to the relative position of the valve 64 to its seat.

In order to assure a supply of fuel under pressure to the reservoir 18 at a time when the usual fuel pump of the engine is inadequate for such purpose, such as when cranking the same during cold weather, an auxiliary pump 96 is provided (see Fig. 8). This pump 96 is manually operable in response to movement of the accelerator pedal (not shown) by means of the arm 34, shaft 28 and a linkage connected to the shaft to be hereinafter described. The pump comprises a cylinder 97 which is open at one end and closed at the other by means of a wall 98. The wall 98 has an inlet opening 99 which is engaged by a check valve 100 maintained in the seated position by means of a compression spring 101, having one end of the spring engaging the valve 100 and the other end abutting a wall 102 having a fuel passage 103 therethrough. A piston 104 is reciprocally mounted in the cylinder 97 and is open at one end and closed at the other by a wall 105 having a fuel passage 106 extending therethrough. The fuel passage is controlled by means of a check valve 107 spring-urged into closed position by a spring 108 resting thereagainst and against a pin 109 extending into the piston walls. The springs 101 and 108 are of a strength such as to merely assure the proper seating of the valves 100 and 107, and the pressure of the fluid within the reservoir will act in a direction to move said valves to the closed position. The pump 96 is mounted with-

in the reservoir at a position to align the opening 99 therein with the opening 73 and is secured in place such as by means of a welded joint as at 110. It will be herein noted that all fuels entering the reservoir under pressure will pass freely through the pump 96.

The piston 104 is reciprocated by means of a shaft 111, one end of which extends into the reservoir and carries a crank arm 112 connected to the piston by means of links 113 which are pivotally attached at one end thereof to the arm 112 and at the other end to the pin 109. The shaft 111 is journaled in a bearing 114 (see Fig. 3) which is secured to the wall 77 of the reservoir in any appropriate manner. The shaft extends beyond bearing 114 and also carries a second crank arm 116 which may be adjustably secured thereto by means of a screw 117. Rocking the crank 116 will in turn rock the shaft 111 and the arm 112 attached thereto to reciprocate the piston 104 and draw fuel into the reservoir through the fuel passages in the pump from a supply connected thereto. In order to prevent leakage of fuel between the shaft 111 and the bearing 114 so as to maintain the pressure in the reservoir 18, a stuffing box 118 is provided, the details of which are not shown and may be of any well-known device used for such purpose.

The pump 96 is arranged to be actuated by the motion of the shaft 28. Accordingly, a crank arm 119 (see Fig. 7) is attached to the end portion 29 of the shaft 28. A rod 120 has one end thereof pivotally attached to the arm 119 and its other end to a yielding resilient connection designated generally 121 (see Fig. 7) secured to the arm 116. This connection comprises a member 122, the end portions 123 and 124 of which are bent substantially at right angles to extend parallel to each other and are provided with suitable openings through which the rod 120 passes. An abutment 125 is adjustably secured to the upper portion of the rod, such as by means of a screw 126. A tension spring 127 has one end anchored to the abutment 125 such as by extending about the screw 126 with its other end secured to the member 122 whereby the abutment 125 and the strap 122 are maintained in engagement with each other by the tension of the spring 127. The arm 116 is pivotally attached to the strap 122 as at 128. When the shaft 28 is rocked, the motion thereof will be transmitted by the connection, above described, to actuate the pump 96. Thus, an arrangement is provided for absorbing any excess movement of the rod 120 beyond that required to move the piston 104 to the upper limit of its travel.

It is desirable that the fuel mixture may be varied according to engine demand and in an automatic manner. To this end (see Fig. 1), a cylinder 130 in which a piston 131 is reciprocated is attached to the conduit 16 and communicates with the air passage therein by means of an opening 132 extending through the wall of the conduit inwardly of the throttle valve 25 so as to relate the movement of the piston to the suction of the engine. The piston 131 will be moved inwardly by the suction of the engine and is spring loaded to move outwardly upon a predetermined drop in engine suction. The term piston is herein employed in a broad sense and may include a diaphragm arranged to be actuated by engine suction. The motion of the piston 131 is transmitted to the shaft 69 by means of linkage and cam motions designated generally 133 (see Fig. 1) which comprise a lever 134 which is made in a manner so as to permit extremely fine adjustment

in the setting of the cam 68. The lever 134 comprises a collar-like member 135 (see Fig. 10) having a reduced portion 136 on which is movably mounted an arm 137 having a depending portion 138 at the free end thereof. The other end of the arm 138 has a projection thereon providing a lip 139 which has a threaded opening therein for receiving an adjusting screw 140. Also secured to the reduced portion 136 (see Fig. 10) so as to move therewith is a second arm 141 carrying a lip 142 positioned to be engaged by the screw 140. The lips 139 and 142 are spring loaded to move towards each other by a tension spring 143, one end of which is attached to the arm 137 as at 144 with the other end thereof attached to the arm 141 as at 145. The lever 134 is adjustably secured to the free end of the shaft 69 as by means of a screw 146. Turning the screw 140 will move the arm 142 to move the cam 68 relative to the valve 64.

The portion 138 of the lever 134 depends into engagement with the free end portion of a lever 147 (Fig. 1) which is pivotally mounted at the other end as at 148 to a movable support 149. The lever 147 is supported on a roller 150 which is mounted to one end of a link 151 the other end of which is pivoted as at 152 to an arm 153. The arm 153 is pivotally secured at the upper end to a pivot 154 on support 155 carried by the body 20. The longitudinal edge of the lever 147 which engages with the roller 150 extends on a curvature of an arc described from substantially the center of the pivot 154 and provides a cam surface 156 which is movable over the roller 150 mechanically by means to be hereinafter described to raise or lower the free end portion of the lever 147 which in turn moves the lever 134 to turn the shaft 69. A second lever 157 is pivotally mounted at one end as at 158 to the support 155 at a position adjacent to the free end of the lever 147 and extends therefrom in spaced relation to the lever 147. The longitudinal edge of lever 157 on the side thereof adjacent the lever 147 also extends on a curvature of an arc described from the center of the pivot 154 and provides a cam surface 159 on which the roller 150 is supported. A roller 160 is carried at the free end portion of the lever 157 and is engageable with a cam 161 which is adjustably secured to the shaft 30 by means of a screw 162 (see Fig. 10). Rocking the shaft 30 as by means of the crank arm 34 will raise or lower the lever 157 which in turn will raise or lower the free end of the lever 147 to open or close the valve 64.

The roller 150 is manually moved between the levers 147, 157 along the length thereof and its position relative to the ends of the levers determined by the characteristic and fuel mixture ratio-demand of the particular engine to which the device may be attached. The position of the roller 150 is also determined by temperature. In cold weather the roller 150 will be moved nearer to the pivot of the lever 147 whereby providing for a greater movement of the lever 147 in response to movement of the cam 161, thereby providing for an increased nozzle valve opening to supply a richer fuel mixture ratio. When the roller 150 is moved in the opposite direction or towards the pivot of the lever 147 a decreased tilting of the lever 147 will be had in response to movement of the cam 161. The limit of movement of the roller 150 in the direction to provide a decreased tilting of the lever 147 and thereby restricting the fuel is set by means of an adjust-

able member 163 which has a threaded shank portion 164 and an enlarged head 165, the outer surface of which may be graduated in equal divisions 166 (see Fig. 6). The member 163 (Fig. 1) threadedly extends through a support 167 into engagement with an abutment 168 carried by the arm 153 and is spring-urged into engagement therewith by a tension spring 169 having one end thereof fastened to the arm as at 170 and the other end to the support 167. A pointer 171 is fastened in any suitable manner to the support 167 and extends therefrom to a position at the edge of the head 165 so as to provide a datum point 172 for the graduation 166. Should the preset position of the roller 150 require changing, the member 163 may be turned in proper determined required amounts with the aid of the graduation 166. As previously mentioned the valve 64 is also mechanically controlled automatically in response to engine operation. To this end the support 149 to which the lever 147 is pivoted is movably mounted as at 173 to a link 174 (see Fig. 4) the upper end of which is secured to turn with shaft 175 (Fig. 4) journaled in the support 176. The pivot 173 also pivotally supports a lever 177 (see Figs. 1 and 5) which is provided intermediate the ends thereof with a projection 178 in line to engage with an extension of the shaft 175. The upper end portion of the lever 177 is connected by means of a rod 179 to a link 180 extending from the piston 131. A tension spring 181 is attached at one end to the lower portion of the lever 177 as at 182 and the upper end thereof is anchored to a projection on lever 149 whereby applying a resistance to the lever tending to move the same in a counter-clockwise direction as viewed in Figure 1. With the engine in action the piston 131 will be drawn within the cylinder 130 by the suction in the conduit 16. Upon a decrease in suction in the conduit 16, the piston 131 will tend to move outwardly and through the linkages just described, the lever 147 will be moved to the right over the roller 150 as viewed in Fig. 1 and tilt the free end of the lever upwardly to move the valve 64 to increase the opening at the fuel passage in the nozzle. Upon the regain of engine torque the suction will increase to draw the piston 131 inwardly and move the lever 147 to the initial position.

Moving the lever 147 along the roller 150 which, in effect, provides a fulcrum about which the lever 147 swings, will raise the free end portion thereof in amounts in accordance to the relative position of the roller 150 on the cam surface 156. A maximum upward movement of the free end of lever 147 will be had when the roller is at a position on the surface 156 nearer to the free end of the lever 147. The minimum raising motion of the lever 147 will be had when the roller is positioned to extend substantially vertically in line with the axis of the pivot 154.

A bracket 183 (see Fig. 2) is carried by the shaft 175 and depends therefrom and threadedly receives a top screw 184 having an enlarged head 185 which may be graduated similar to the head 165. A pointer 186 provides a datum line for the graduations on the head 185. The end of the screw 184 extends into engagement with the side of the body 20 and provides a stop to limit the inward movement of the support 149. A threaded stud 187 is also attached to the shaft 175 so as to move therewith and receives thereon an adjusting member 188 which supports one end of a tension spring 189, the other end of which is secured to a projection 190 extending from the side of the

conduit 16. The spring 189 provides a resistance to the inward movement of the piston 131. This resistance may be varied by turning the member 188 along the length of the member 187 whereby changing the point of application of the resistance force on member 187. In order to predetermine the position of the member 188 along the member 187, index 191 properly graduated along the edge thereof may be positioned to extend parallel to the member 187.

The operation of the device is as follows: assuming the parts to be in proper relation to each other, and the throttle 25 in the closed position, the cranking of the engine will, under normal conditions, produce a sufficient suction in the air conduit 16 to move the piston 131 inwardly, as shown in Figure 1. This will swing the lever 177 about its mounting 173 and move the support 149 down and to the left, as viewed in Figure 1. This motion lifts lever 134 and turns stem 47 to lift valve 64 from its seat 53. The motion of support 149 will move the lever 147 along the roller 150 through its engagement with the cam face 156 of the lever to raise the free end of the lever 147 into engagement with the portion 138 of the lever 134 to move the same to further open or lift the valve 64, Figure 10, from the seat 53 to the idling and cranking setting. Also, assuming that sufficient pressure has been built in the reservoir 18 by means of the engine pump P connected by means of conduit C to the reservoir 18, fuel will under pressure flow through the bore 42 of nozzle 17 and through the various passages therein out through the opening 52 in a fine mist into the air flowing by the nozzle. This fuel in this form will mix with the air as it is drawn into the engine intake manifold 24 in a usual manner. By means of the accelerator pedal (not shown) the arm 34 may be rotated in the direction so that the cam 161 thereon engaging with the roller 163 will raise the lever 157, which motion will be transferred through the roller 150 to the lever 147 to swing the same about its pivot 148 to move the lever 134 to increase the flow of fuel from the nozzle 17. The moving of the lever 34 will also open the throttle 25 through its connection 31, 32, 27 therewith. Upon a load being placed upon the engine such as when the engine is propelling a vehicle up a hill, the speed of the engine will be reduced with a resultant drop in the suction in the conduit 16. This drop in suction will permit the piston 131 under pressure of the spring 189 to move outwardly in an amount depending upon the degree of drop in engine suction. The motion of the piston will be transmitted to lever 177 and swing the same about its pivot 173 in a counter-clockwise direction moving the support 149 to the right, as viewed in Figure 1, to move the lever 147 over the roller 150 and thereby raise the lever 134 to turn the valve controlled shaft 69 in a direction to further move the valve 64 from the seat 53 and provide for an increase in fuel ejected into the air stream thereby enriching the same.

In order to manually remotely control the position of the roller 150, a wire or rod 200 is secured to the arm 153 as by a connection 201 and may be extended to the dash panel of the vehicle.

In order to control the response of the piston 131 to the suction of the engine, the spring 189 is adjustable along the member 187 whereby to increase or decrease the leverage provided by such spring on the shaft 175 which in turn provides a resistance to the inward movement of the piston 131. Thus, the arrangement may be

provided whereby a slower response to the suction change may be made in the actuation of the needle valve 64. In other words, the device may be made to respond quickly to any change in suction or may be delayed, as the choice may be.

At such time as when the engine is not being cranked sufficiently fast to operate the pump P of the engine such as during extremely cold weather, the auxiliary pump 96 may be brought into action by a manual motion of the arm 34 whereby to draw and build up a pressure sufficiently into the reservoir 18 to supply fuel to the air flow in the conduit 16.

With the engine operating at low speed and fully opened throttle the suction in the intake manifold may be reduced to an extent to be insufficient to maintain the piston 131 in the inward position which would result in a movement of the lever 177 to permit the member 149 to swing upwardly to close the valve 64. In order to provide for such condition of operation such as would be experienced in ascending a step grade, means are provided for holding the member 149 in the valve opened position. This comprises an arm 202 (see Fig. 4) which is movably mounted on the shaft 30 and is provided with an abutment 203. A torque spring 204 (see Fig. 10) surrounds the shaft 30 and has one end thereof secured to the lever 202 and the other end extends into engagement with an abutment 205 (Fig. 4) which may be secured to the cam 161 or other structure movable with the shaft 30 whereby the arm 202 will be spring urged to move the abutment 203 thereon into engagement with the abutment 205. The arm 202 is connected to a projection 209 which extends from the lower edge of the support 149 by means of a member 206 which is provided with a slot 207 in which the reduced portion 208 of the abutment 203 is received. Upon maximum movement of the arm 34, the reduced portion 203 will engage with the lower edge of the recess 207 thereby swinging the member 149 about its mounting 173. Upon further movement of the arm 34 to move the lever 177 to increase the opening of the discharge nozzle, the arm 202 will be prevented from further movement, and the force of the spring acting thereon will maintain the member 149 in the position shown, such as in Figure 2 until the suction of the engine actuates the piston 131 to maintain the support 149 in engagement with the member 206. Upon the moving of the cam 161 in the opposite direction, with the engine at rest and the cam turned to its lowermost position, the link 178 will be moved through the action of the spring 131 on the lever 177 to swing the free end of the support 149 upwardly as shown in dot and dash line in Fig. 5 whereby causing the free end of the lever 167 to drop out of engagement with the depending portion 138 of lever 134 and freeing the lever 134 so as to permit the spring loaded valve 64 to positively close the nozzle.

I claim:

1. In combination with an internal combustion engine having a fuel pump, a fuel atomizer for said engine comprising an air flow conduit adapted to be attached to the intake manifold of the engine, a throttle valve in said conduit for controlling the admission of air in said conduit, a fuel nozzle in said conduit for ejecting fuel under positive pressure in the air flowing through said conduit, a fuel reservoir connected to said nozzle, said pump delivering and maintaining fuel under pressure in said reservoir,

75

means in said reservoir for dampening pulsation of the fuel in said reservoir, and an auxiliary pump manually operable for supplying fuel to said reservoir.

5 2. In combination with an internal combustion engine having a fuel pump, a fuel atomizer for said engine comprising an air flow conduit adapted to be attached to the intake manifold of the engine, a throttle valve in said conduit for controlling the admission of air in said conduit, a fuel nozzle in said conduit for ejecting fuel under positive pressure in the air flowing through said conduit, a fuel reservoir connected to said nozzle, said pump delivering and maintaining fuel under pressure in said reservoir, a spring-pressed diaphragm in said reservoir for dampening pulsation of the fuel in said reservoir, and an auxiliary pump positioned within said reservoir and manually operable for supplying fuel to said reservoir.

25 3. A fuel atomizer for an internal combustion engine comprising an air flow conduit adapted to be attached to the intake manifold of the engine, a throttle valve in said conduit for controlling the admission of air in said conduit, a fuel nozzle in said conduit for ejecting fuel under positive pressure in the air flowing in said conduit, a fuel reservoir connected to said nozzle, means in said reservoir for dampening pulsation of the fuel in said reservoir, and a pump in said reservoir manually operable for supplying fuel to said reservoir under pressure above atmospheric.

35 4. A fuel atomizer for an internal combustion engine comprising an air flow conduit adapted to be attached to the intake manifold of the engine, a fuel nozzle in said conduit for ejecting fuel under positive pressure into the air flowing through said conduit, valve means in said nozzle for controlling the amount of fuel delivered through said nozzle in response to engine operation, a movable support, a lever pivotally secured to said support with the free end thereof operatively connected to said valve, and movable to open or close said valve, a shiftable guide member providing a surface for engaging and tilting the free end portion of said lever, and suction actuated means movable in response to engine suction for moving said support for tilting the lever about said shiftable guide member to open or close said valve in response to variation in engine suction under load.

55 5. A fuel atomizer for an internal combustion engine comprising an air flow conduit adapted to be attached to the intake manifold of the engine, a fuel nozzle in said conduit for ejecting fuel under positive pressure into the air flowing through said conduit, valve means in said nozzle for controlling the amount of fuel delivered through said nozzle in response to engine operation, a movable support, an arcuate lever pivotally secured to said support and operatively connected to said valve and movable axially to open or close said valve for controlling the amount of fuel delivered through said nozzle, a shiftable guide member providing a surface over which said lever is moved for tilting the same, and means actuated in response to engine suction for moving said support for moving said lever over said shiftable member to open or close said valve in response to variation in engine suction under load.

6. A fuel atomizer as set forth in claim 4 wherein a yielding resistance is provided for opposing the movement of said suction actuated means.

7. A fuel atomizer as set forth in claim 6 wherein yielding resistance is adjustable.

8. A fuel atomizer for an internal combustion engine comprising an air flow conduit adapted to be attached to the intake manifold of the engine, a fuel nozzle positioned within said conduit for ejecting fuel under positive pressure into the air flowing through said conduit, valve means in said nozzle for controlling the amount of fuel delivered through said nozzle in response to engine 10 operation and cam operated means for controlling said valve means comprising a pair of levers and a shiftable fulcrum member for one lever engageable between said levers and through which motion is transmitted from one lever to the other.

9. A fuel atomizer for an internal combustion engine comprising an air flow conduit, a fuel nozzle for ejecting fuel under positive pressure into the air flowing through said conduit, a discharge opening in said nozzle, a needle valve for controlling the flow of fuel through said opening, a pair of levers operatively connected to said valve and manually rockable for moving said valve to and from said opening, said levers being arranged for providing a compound movement 25 therebetween and a shiftable fulcrum member for one lever through which said levers operate.

10. A fuel atomizer for an internal combustion engine comprising an air flow conduit adapted to be attached to the intake manifold of the engine, a fuel nozzle for ejecting fuel under positive pressure into the air flowing through said conduit, variably opening valve means in said nozzle for controlling the amount of fuel delivered through 30 said nozzle, a pair of pivoted levers extending toward each other with the free end portion of one of said levers operatively connected to said valve means, a shiftable fulcrum member for one lever positioned between said levers and engageable therewith and through which motion is transmitted from one lever to the other, and a cam for engaging the other of its levers for moving the said free end portion operating said valve means.

11. In a fuel atomizer for an internal combustion engine an air flow conduit adapted to be attached to the intake manifold of the engine, a fuel nozzle in said conduit operable under positive pressure for ejecting fuel in the air flow in said conduit, a reservoir for the fuel connected to said nozzle, and a fuel pump positioned within said reservoir for supplying fuel thereto, a diaphragm in said reservoir operable for dampening pulsation of the fuel in said reservoir.

12. A fuel atomizer for an internal combustion engine comprising an air flow conduit adapted to be attached to the intake manifold of the engine, a fuel nozzle for ejecting fuel under positive pressure into the air flowing through

said conduit, a reservoir for supplying fuel to said nozzle, a pump positioned within said reservoir for supplying fuel thereto, valve means in said nozzle for controlling the amount of fuel delivered through said nozzle in response to engine operation and means operable for opening and closing said valve means, said fuel nozzle and said reservoir being attached to each other providing a unit structure secured to said conduit.

13. In combination with an internal combustion engine having a fuel pump, a fuel atomizer for said engine comprising an air flow conduit adapted to be attached to the intake manifold of the engine, a throttle valve in said conduit for controlling the admission of air in said conduit, a rotatable shaft, means for mounting said throttle valve onto said shaft, a fuel nozzle in said conduit through which fuel is discharged into the air flow of said conduit, a fuel reservoir connected to said nozzle, means including the engine pump for supplying fuel to said reservoir under pressure above atmospheric whereby to eject the fuel under positive pressure through said nozzle, an auxiliary pump manually operable for supplying fuel to said reservoir, means connecting said shaft to said pump to operate said auxiliary pump upon rotation of said shaft to supply fuel to said reservoir and means for rendering said pump inactive upon a predetermined pressure in said reservoir.

14. In combination with an internal combustion engine as set forth in claim 13 wherein said auxiliary pump is positioned within said reservoir.

THEODORE N. SAATY.
